SUPPLY HOLDERS

Ernest R. Swanson, Cranston, R. I., assignor to
Universal Winding Company, Boston, Mass., a
corporation of Massachusetts

Application November 17, 1936, Serial No. 111,295

19 Claims. (Cl. 242—35.5)

This invention relates to supply holders for supporting cops, bobbins or other forms of packages of yarn, thread and the like to deliver the material to winding machines or other textile apparatus.

In the following specification and claims the term "bobbin" is to be interpreted in a generic sense as applying to any preferred form of supply, and the term "yarn" is employed in a broad sense to designate all varieties of strand material.

One object of the invention is to provide a supply holder which will facilitate and expedite the doffing of spent bobbins and the placing of fresh bobbins in delivering position.

Another object of the invention is to provide a supply holder of the type indicated from which the spent or exhausted bobbins may be doffed or ejected by simply pressing a button or push-rod.

Another object of the invention is to provide a device of the type indicated which acts to positively eject the spent or exhausted bobbin from the supply-spindle and which operates automatically, upon release of the manual control means, to quickly return the spindle to delivering position to receive a fresh bobbin.

Another object of the invention is to provide a device of the type indicated which is adjustable with respect to the winding or like machine to insure proper delivery of the yarn thereto.

Another object of the invention is to provide a device of the type indicated which is of sturdy construction with its parts proof against derangement or getting out of order.

Further objects of the improvement are set forth in the following specification which describes a preferred form of construction of the invention, by way of example, as illustrated by the accompanying drawings. In the drawings:

Fig. 1 is a front view of a conventional type of winding machine showing the present improved supply holder as applied to use therewith;

Fig. 2 is a plan view of the supply holder shown in connection with the tension-device with which it cooperates;

Fig. 3 is a side elevation of the supply holder showing the bobbin chute or runway in section;

Fig. 4 is an elevational view of the supply holder looking in the direction indicated by the arrow 4 in Fig. 2 and showing a supply-bobbin in position to deliver the yarn to the winding machine;

Fig. 5 is a view similar to Fig. 4 illustrating the manner in which the empty bobbin is doffed or ejected from the supply-spindle; and

Fig. 6 is a sectional plan view of a portion of the holder taken on line 6—6 of Fig. 3.

In general, the present invention comprises a spindle or other means for holding a bobbin or the like in delivering position, a chute or runway for guiding a full bobbin into position upon the spindle, means for manually tilting the spindle into doffing position, means operated by the tilting action of the spindle for stripping or ejecting a spent bobbin therefrom, and automatically-operated means for returning the spindle into position to receive a fresh bobbin.

The invention is herein shown as applied to use on a winding machine for winding thread, yarn and other strand material, but the device is also adapted for use with other types of textile apparatus in which yarn or the like is transferred from one carrier to another in various processes of the textile art.

Referring to the drawings, the winding machine herein illustrated, by way of example, is of conventional type in which the package is rotated by peripheral contact with a drive-roll or drum. The present supply-holder is adapted for use with practically all types of winding and like machines however, and therefore the illustrated machine will be described only briefly as relating to the operation of the improved device.

A plurality of winding units are usually mounted upon a bed or frame 2 supported from the floor by legs 3 spaced along the machine. The bed 2 carries brackets 4 which, in turn, support bearings for the rotative elements of the winding mechanism. The winding mechanism of the individual unit herein illustrated comprises only two principal elements, namely, the winding-mandrel or spindle 5 on which the yarn-receiver or cop-tube C is rotatably supported and the drive-roll 10 for rotating the yarn-receiver; and in which is embodied means for traversing the yarn back and forth axially of the package being wound. This particular form of traversing means is fully shown and described in United States Letters Patent No. 1,749,355, dated March 4, 1930.

The drive-rolls 10 for the several winding units are carried on a horizontal shaft 13 journaled in bearings supported by the brackets 4 and continuously driven from a suitable source of power. The machine is herein shown as adapted for winding packages of conical form in which the yarn body or package is built up on a suitable core or receiver, a wooden or fiber cone C being illustrated as mounted to rotate on the winding-spindle 5. The spindle 5 is hingedly mounted at the forked end of an arm 15 which is pivoted

on a rod or stud 16 held in a bearing 17 projecting from the top of the bracket 4. The arm 15 is usually weighted to cause the surface of the yarn-receiver C or of the package, as the case 5 may be, to be held firmly in contact with the periphery of the drive-roll 10 and as the yarn is built up on the receiver it forces the latter upwardly with the arm 15 pivoting on its stud 16.

The supply of yarn is usually arranged below 10 the winding mechanism and, as herein shown, a supply-bobbin B is mounted upon a rockable spindle 50 which forms an essential element of the improved supply-holder.

Each unit of the winding machine is usually 15 provided with a tension-device for controlling the draft of the yarn as it feeds to the cop or package being wound, and the present drawings illustrate a disk-tension means 18 for this purpose. The tension-device 18 is mounted upon a horizontal rod 19 which is supported in brackets 20 secured to the legs 3 of the machine by means of clamps 21 and one or more bolts 22, as shown in Fig. 2. The tension-device comprises a two-part bracket 25, one half of which supports a horizontal pin 26. A pair of tension-disks 27 mounted for rotation on the pin 26 provide the means for applying resistance to the passage of the strand of 20 yarn drawing therebetween.

The strand of yarn y leads through an opening 30 or slit 28 at one side of the bracket 25 and draws between the two tension-disks 27. From the tension-disks the strand y leads through a suitable slub-catcher, not herein shown, and thence through the grooves in the transverse-roll 10 to be fed therefrom and traversed thereby onto the cop or package being wound. The opening or slit 28 will be hereinafter referred to as the delivery 35 point of the yarn since it is to this point that the strand is directed from the supply-bobbin B.

In delivering yarn or other strand materials 40 from cops, bobbins and other types of headless packages, the strand is usually drawn off over the end of the package and for winding machines the supplies are generally arranged below the winding units with their axes in line with the delivery point to which the yarn leads as it feeds through the tension-device. In the present embodiment of the invention as applied to a winding machine the supply holders, one for each winding unit, are supported from a horizontal rod 34 which extends 45 between arms or brackets 35 attached to the legs 3 of the machine. As shown in Figs. 1 and 2, the brackets 35 are fastened to the web of the legs 3 by means of clamps 36 secured in place by bolts 37, and the rod 34 is held in hubs 38 at the 50 ends of the brackets 35.

Adjustably mounted on the rod 34 below the tension-devices 18 are brackets or supports 40. Each bracket 40 comprises a hub 41 surrounding 60 the rod 34 and a boss 42 projecting thereabove and supporting the end of a pivot-stud or rod 43 which is secured in place therein by a set-screw 44, see Fig. 2. The pivot-stud 43 extends forwardly and downwardly from the boss 42 at an angle to the horizontal and serves to pivotally mount a member 45.

The member 45 is constructed with a hub 46 bored to receive the pivot-stud 43 and a horizontal arm 47 extending laterally from the hub and 70 formed with a boss 48 at its end. The boss 48 is provided with a vertical bore for receiving the supply-spindle 50 which is secured therein by a set-screw 51. The spindle 50 is preferably beveled at its upper end to facilitate the placing of 75 a supply-bobbin B in position thereon. The

upper end of the boss 48 is beveled as indicated at 52 to adapt it to receive the tapered end of the bore of the supply-bobbin B and is provided with a recess 54 in its side for a purpose as later explained. A weighted arm 55 formed integral with the member 45 extends laterally from the hub 46 in a direction opposite to that of the extension or arm 47 to provide a counterweight which functions for a purpose as later explained.

Rising from the extension or arm 47 of the member 45 is a bifurcated stanchion 56 and extending between the sides of its bifurcated portion is a pin 57. Pivoted on the pin 57 between the sides of the stanchion 56 is a lever or ejector-member 60 having a pointed end 61 which is bent laterally at an angle to adapt it to enter the recess 54 in the boss 48 of the arm 47 as illustrated in Figs. 4 and 6. A projection or toe 62 formed integral with the lever 60 and extending from the opposite side of its pivot 57 functions for a purpose as later explained.

The supply-spindle 50 is swung upwardly from its operative position shown in Fig. 4 to the doffing position illustrated in Fig. 5 by the operation of manually-controlled means constructed and arranged as next described. Projecting radially from the hub 46 of the member 45 is an arm 64 formed with a hole at its end for receiving the lower hooked end of a wire control-rod 65. The rod 65 extends upwardly through a hole 66 in a projection 67 of a collar 68 secured in place on the tension-rod 19 by a set-screw 69. The upper end of the rod 65 may be provided with a finger-piece or push-button 70 adapted to be pressed downwardly by the operator when it is desired to doff the empty supply-bobbin from the spindle 50. The lower end of the control-rod 65 is held in place in connection with the arm 64 by means of a quadrant-shaped plate 72 projecting from the hub 73 of a stop-member 71 secured to the end of the pivot-stud 43 by a set-screw 74. An arm 75 projects from the opposite side of the hub 73 of the member 71 and is provided with a stop or abutment 76 upon which the arm 47 of the member 45 normally rests.

During the doffing operation the supply-spindle 50 is swung rapidly to the position shown in Fig. 5 and this movement, augmented by the force of momentum, is usually sufficient to cause the empty bobbin b to be thrown off therefrom. However, to insure positive ejection of the bobbin the present invention contemplates the use of the ejector-member 60 previously referred to. As shown in Figs. 4 and 5 an inclined arm 79 projects from the hub 73 of the stop-member 71, being provided at its end with a laterally-projecting arcuate stop 80 for engaging the toe 62 of the ejector-member 60 when the latter is swung upwardly with the movement of the arm 47 of the member 45. The stop-member 71 is adjustable about the stud-shaft 43 to aline the supply-spindle 50 with the slit or delivery point 28 and to position the stop 80 to effect proper cooperation with the toe 62 of the ejector-member 60.

Adjustably mounted on the rod 19 and secured 65 in place by means of a set-screw 84 is a collar 85, see Fig. 2. Projecting from the collar 85 is an elbow-shaped rod 86 which reaches forwardly and downwardly to serve as a support for a trough-shaped chute or runway 90. As shown in 70 Figs. 1 and 2, the chute 90 is provided with a laterally extending boss 87 having a hole for adjustably mounting it on the rod 86, a set-screw 88 serving to hold the chute in its adjusted position. The chute or runway 90 provides means 75

for guiding a full bobbin B into place on the supply-spindle 50 when it is desired to replenish the supply. The chute 90 is inclined to the vertical at a slightly greater degree than the spindle 50 to provide that after the bobbin B has slid down the chute into position with its lower end impaled on the end of the spindle, further sliding movement of the bobbin will cause it to tilt upwardly away from the chute as shown in Fig. 3. 10 The improved supply holder having now been described in detail its method of operation will next be explained.

Assuming that a full bobbin B is in place on the spindle 50 of the supply holder as shown in Fig. 1 of the drawings, the strand y is drawn upwardly through the slit 28 in the bracket 25, threaded between the tension-disks 27, laid across the traverse-roll 10 and its end attached to the cop-tube C. The spindle-arm 15 is then lowered to place the periphery of the cop-tube C in contact with the rotating drive-roll 10. The roll 10 rotates the cop-tube to wind the yarn thereon as the grooves in the roll traverse the strand back and forth to deposit it in helical coils which build up in layers to form the package. As the winding proceeds and the yarn is taken off from the bobbin B, eventually the end will run out and the operation of the machine is automatically arrested through the action of a suitable stop-motion, not herein shown.

The supply-spindle 50 is normally maintained in substantially vertical position, as viewed in Fig. 1, under its own weight and that of the bobbin B and the arm 47 with the arm resting against the stop 76. Owing to the inclination of the stud 43 the spindle 50 is inclined slightly with respect to a vertical plane extending longitudinally of the machine, see Fig. 3, to provide that the bobbin B will be axially alined with the delivery point 28 in the tension-device 18. It will be observed by reference to Figs. 1 and 4 that with a bobbin B in place on the spindle 50 the pointed end 61 of the ejector-member 60 is positioned in the recess 54 of the arm or extension 47 beneath the head of the bobbin.

When it is observed that the yarn on the bobbin B is almost exhausted the operator takes his station at the front of the supply holder and immediately the winding has been arrested the push-button or finger-piece 70 is pressed downwardly. The downward sliding movement of the control-rod 65 rocks the member 45 on its pivot 43 to cause the arm 47 to rotate in a clockwise direction as viewed in Figs. 1, 4 and 5. This movement of the member 45 is aided by the counterweight 55 so that only a slight pressure is required on the push-button 70 to perform the operation. As the arm 47 and spindle 50 are swung upwardly the ejector-member 60 moves with them until its toe 62 strikes the stop 80. Further upward movement of the arm 47 causes the ejector-member 60 to be rocked upwardly about its pivot 57 with a quick action. The movement of the ejector-member 60 is more rapid than that of the spindle 50 and its toe 61 ejects the empty bobbin b from the spindle 50 and propels it to one side of the supply holder or in the direction indicated by the arrow in Fig. 5. The swinging movement of the several parts is limited by the engagement of the push-button 70 against the projection 67 of the collar 68. A box or like receptacle may be provided to receive the ejected bobbins b or in other cases they may

drop onto a traveling conveyor which removes them from the machine.

It is to be particularly noted that although the ejection of the bobbin is above explained as being caused by the action of the ejector-member 60, the use of this element is not essential. That is to say, if the spindle 50 is swung upwardly rapidly, as provided for by the relatively short leverage of the arm 64 to which the push-rod 65 is connected, the force of momentum will propel the bobbin off from the end of the spindle. On the other hand, the ejector-member 60 is provided as a precautionary measure to insure a positive ejection of the bobbin should the operator press the push-rod 65 down too slowly.

Immediately the empty bobbin b has been doffed in the manner as above explained the operator releases the push-button 70 and the weight of the arm 47 and the parts carried thereby returns the member 45 to first position as illustrated in Fig. 4, with the arm 47 resting upon the stop 76. During the return of the member 45 the counterweight 55 acts to control its movement to prevent rebound as the arm 47 strikes the stop 76. With the arm 47 at rest the supply-spindle 50 will again be alined with the delivery point 28 of the tension-device 18 to insure proper delivery of the yarn thereto. It will be understood that during the return movement of the parts in the manner above explained the ejector-member 60 swings downwardly about its pivot 57 under the action of gravity to position its pointed end 61 in the recess 54.

After the supply-spindle 50 has been returned to first position the operator places a fresh bobbin B in the chute 90 and releases it to permit it to slide downwardly under the action of gravity while he holds the end of the yarn. As the bobbin B slides downwardly in the chute in the manner indicated by the dash lines in Fig. 3 the beveled end of the spindle 50 enters its bore to impale it thereon. Due to the angular relationship of the chute 90 to the spindle 50 the bobbin B is canted upwardly away from the chute as it slides onto the spindle in the manner indicated by full lines in Fig. 3 to aline its axis with the delivery point 28 in the tension-device 18. The fresh bobbin B is then in position to supply yarn to the winding unit and the end of its strand is led upwardly through the tension-device 18 and spliced to the trailing end on the package being wound.

It will be observed from the foregoing that the present invention provides a particularly simple yet efficient device for the purpose specified. The improved supply holder is practically entirely automatic in operation, the operator having only to press the button to effect the doffing of the empty bobbin and to then place a fresh bobbin in the chute to cause it to be impaled on the spindle in delivery position.

The bobbin-chute is placed in inclined position to enable the operator to quickly and conveniently drop the bobbin thereinto. The holder is placed in close relationship with the tension-device and in elevated position to provide that the end of the strand may be readily threaded through the tension-device without requiring stooping or reaching on the part of the operator.

The invention thus provides for a substantial saving in the time usually required for doffing spent bobbins and supplying fresh ones in their place. Moreover, less effort and energy is used and the operator's strength conserved for other duties. The saving in time and effort is re-

flected in a considerable increase in the productive capacity of the machine.

While the improved device is herein shown and described as embodied in a preferred form of construction and as applied to a winding process, various modifications may be made in the form and arrangement of its parts and in its method of application to other processes without departing from the spirit or scope of the invention.

10. Therefore, without limiting myself in this respect, I claim:

1. In a device of the type indicated, a rockable support, means for mounting a bobbin on the support remotely from the axis about which the latter rocks with its axis tangent to an arc concentric with the pivotal axis of said support, and 15 slideable means operatively connected to rock the support, said rocking movement of the support acting to propel a spent bobbin axially to automatically eject it from the support by the force of 20 momentum.

2. In a device of the type indicated, a rockable support for bobbins, means for mounting a bobbin on the support remotely from the axis about which the latter rocks with its axis tangent to an arc concentric with the pivotal axis of said support, means for rocking the support to propel a spent bobbin axially therefrom, said bobbin being ejected by the force of momentum thereon, 25 and means for returning the support into position to receive a fresh bobbin.

3. In a device of the type indicated, a pivotally mounted support, a spindle for bobbins so positioned on the support as to be moved axially 30 through an arc by the rocking movement of the support, means for rocking the support to move the spindle axially, said axial movement of the spindle causing a spent bobbin to be ejected by the force of momentum, and means for returning 35 the support into position to receive a fresh bobbin.

4. In a device of the type indicated, a pivotally mounted support, means for normally holding the support in substantially horizontal position, a substantially vertical bobbin-supporting spindle on 40 the support positioned laterally of and remotely from its pivotal axis, and means for rocking the support to move the spindle and bobbin axially through an arc, said bobbin being automatically ejected by the force of momentum, and said first- 45 mentioned means including means for returning the support into position to receive a fresh bobbin.

5. In a device of the type indicated, the combination of a pivoted arm, a spindle for bobbins 50 on said arm positioned at one side of its pivotal axis and extending at right-angles thereto, said arm and spindle lying in a plane extending at right-angles to the pivotal axis of the arm, means for rocking said arm to cause the spindle and a spent bobbin to be moved axially through an arc, the force of momentum on the spent bobbin causing it to be automatically ejected from the spindle, and means for returning the spindle into position to receive a fresh bobbin.

6. In a device of the type indicated, the combination of a pivoted arm, a spindle on said arm located at one side of its pivotal axis and so positioned as to move axially as the arm is rocked and adapted to hold bobbins, manually-operative 70 means for rocking said arm on its pivot to swing the spindle axially through an arc to eject a spent bobbin therefrom by the force of momentum, and gravity-responsive means for returning the arm to position the spindle to receive a fresh bobbin.

7. In a device of the type indicated, a pivoted

support, means for mounting a bobbin on the support remotely from the axis about which the latter rocks with its axis tangent to an arc concentric with the pivotal axis of said support, and a manually-operative push-rod connected to the support to rock the latter about its pivot, a spent bobbin on the support being moved axially as the support is rocked to automatically eject the bobbin by the force of momentum acting thereon.

8. In a device of the type indicated, the combination of a counterbalanced pivoted arm suspended horizontally below its pivot, a vertical spindle on the arm positioned remotely from its pivotal axis, said spindle being adapted to hold bobbins, and manually-operative means for rocking said arm on its pivot to swing the spindle axially through an arc to eject a spent bobbin by the force of momentum, said arm being automatically returned by gravity to position the spindle to receive a fresh bobbin.

9. In a device of the type indicated, the combination of a spindle for holding bobbins, means for mounting the spindle to adapt it to move axially through an arc, an ejector movable relatively of the spindle, means for moving said spindle through an arc and actuating the ejector to eject a spent bobbin therefrom, and means for returning the spindle into position to receive a fresh bobbin.

10. In a device of the type indicated, the combination of a spindle for holding bobbins, means for mounting the spindle to adapt it to tilt axially through an arc, an ejector normally positioned below the bobbin and movable longitudinally of the spindle, means for simultaneously tilting the spindle and actuating the ejector to eject a spent bobbin, and means for returning the spindle into position to receive a fresh bobbin.

11. In a device of the type indicated, the combination of a spindle for holding bobbins, an 40 ejector normally positioned below the bobbin and movable longitudinally of the spindle, means for tilting the spindle to move a spent bobbin axially through an arc, said spent bobbin being automatically ejected by the force of momentum, 45 means for actuating the ejector during the tilting of the spindle to augment the force of momentum in ejecting the bobbin, and means for returning the spindle into position to receive a fresh bobbin.

12. In a device of the type indicated, the combination of a tiltable spindle for holding bobbins, a pivoted lever having one end normally positioned adjacent the spindle and below the bobbin and movable longitudinally of the spindle as the 55 lever is rocked, means for tilting the spindle and rocking the lever to eject a spent bobbin, and means for returning said spindle into position to receive a fresh bobbin.

13. In a device of the type indicated, the combination of a pivoted arm, a spindle on said arm for holding bobbins, an ejector carried by said arm and movable relatively of the spindle, means for rocking the arm on its pivot and actuating the ejector to eject a spent bobbin, and means for returning the arm to position the spindle to receive a fresh bobbin.

14. In a device of the type indicated, the combination of a pivoted arm, a spindle on said arm positioned remotely from the pivotal axis thereof and extending at right-angles thereto, said spindle being adapted to hold bobbins, an ejector on the arm movable longitudinally of the spindle, means for rocking the arm to move the spindle axially through an arc, means for actuating the

ejector during the rocking movement of the arm to eject a spent bobbin, and means for returning the arm to position the spindle to receive a fresh bobbin.

5 15. In a device of the type indicated, the combination of a pivoted arm, a spindle on said arm extending at right-angles thereto, said spindle being adapted to hold bobbins, a lever pivotally mounted on said arm with its forward end normally positioned adjacent the spindle below the bobbin and its opposite end extending rearwardly of its pivot, means for rocking said arm to move the spindle axially through an arc, and means for engaging the rearward end of the lever as the 10 arm is rocked to cause its forward end to move longitudinally of the spindle to eject a spent bobbin therefrom.

15 16. In a device of the type indicated, a counterbalanced pivoted arm suspended below its pivot, a stop-member adjacent the arm for normally holding the latter in horizontal position, a vertical spindle on said arm positioned remotely from its pivotal axis, said spindle being adapted to support bobbins, a lever pivotally mounted on said arm intermediate its ends, one end of said lever being positioned adjacent the spindle and below the bobbin, an abutment on the stop-member overlying the opposite end of 20 said lever, and manually-operated means for rocking the arm about its pivot to move the spindle axially through an arc, said abutment on the stop-member engaging one end of the lever as the arm is rocked on its pivot to move the opposite end of the lever longitudinally of the spindle to eject a spent bobbin therefrom, said arm 25

being automatically returned by gravity to position the spindle to receive a fresh bobbin.

17. In a device of the type indicated, the combination of a pivoted support, a spindle on said support positioned remote from its pivotal axis with the axis of the spindle tangent to an arc concentric with the pivotal axis of said support, means for rocking the support to move the spindle axially through an arc to eject a spent bobbin therefrom, means for returning the arm to position its spindle to receive a fresh bobbin, and a chute for delivering a fresh bobbin onto the spindle. 5 10

18. In a device of the type indicated, a pivoted arm normally held in a horizontal position, a vertical spindle on said arm positioned remotely from and at one side of the pivotal axis of the latter, said spindle being adapted to support bobbins, manually-operated means for rocking the arm to move the spindle axially through an arc 20 to eject a spent bobbin therefrom by the force of momentum, gravity-operated means for returning the arm to position the spindle to receive a fresh bobbin, and a chute for directing a fresh bobbin onto the spindle. 25

19. In a device of the type indicated, a support, a spindle on the support for mounting a bobbin having an axial bore, and a chute positioned angularly with respect to the axis of the spindle for guiding the bobbin to aline the bore 30 at its end with the end of the spindle, said bobbin being automatically rocked by its engagement with the spindle from an angular to an axial position with respect to the spindle and away from the chute. 35

ERNEST R. SWANSON.
